HUMIDIFIER

Warner W. Martin, Olmstead Falls, Ohio, assignor to The Lau Blower Company, Dayton, Ohio, a corporation of Ohio

Filed July 6, 1965, Ser. No. 86,022

Term of patent 14 years

(Cl. D62—4)

FIG-1

FIG-6

FIG-7

FIG. 1 is a perspective view of a humidifier showing my new design;

FIG. 2 is a front elevation of my new design;

FIG. 3 is a rear elevation thereof;

FIG. 4 is a top view thereof;

FIG. 5 is a bottom view of my new design;

FIG. 6 is a side elevation view looking from left to right in FIG. 2; and

FIG. 7 is another side elevation view looking from right to left in FIG. 2.

The portions shown in broken lines are included for illustrative purposes only, and do not form part of the invention.

I claim:

The ornamental design for a humidifier, substantially as shown and described.
